UNITED STATES PATENT OFFICE.

JOHN R. KOONS, OF HUNTINGTON MILLS, PENNSYLVANIA.

OUTSIDE DRY-EARTH CLOSET.

No. 811,412.

Specification of Letters Patent.

Patented Jan. 30, 1906.

Application filed September 7, 1904. Serial No. 223,593.

To all whom it may concern:

Be it known that I, JOHN R. KOONS, a citizen of the United States, residing at Huntington Mills, in the county of Luzerne and 5 State of Pennsylvania, have invented new and useful Improvements in Outside Dry-Earth Closets, of which the following is a specification.

My invention relates to improvements in 10 what may be termed "outdoor dry-earth closets or privies."

Said invention has for its object to provide for supplying coal-ashes, earth, or other suitable material to the excrement contained in 15 the box or chamber of the closet or privy as an absorbent for such excrement, rendering the latter odorless and otherwise desirable from a sanitary view-point.

Said invention consists of the combination 20 and arrangement of parts substantially as hereinafter fully disclosed, and particularly defined by the claims.

In the accompanying drawings, illustrating 25 the preferred embodiment of my invention, Figure 1 is a view showing said invention as applied to an ordinary privy or earth-closet, partly in sectional elevation. Fig. 2 is a section produced through the sifter and its chamber portion of the device at right angles to the plane of Fig. 1. Fig. 3 is a plan view of the parts contained in Fig. 2 with the top part of the casing removed. Fig. 4 is a broken-away detailed view disclosing more especially the lower interior portion of the 30 sifter-chamber with its structural features. Fig. 5 is a view showing particularly the sifter moved outward and its pivoted bottom tilted, as in dumping its coarse particles after the sifting operation. Fig. 6 is a vertical 35 cross-section produced through the excrement box or chamber, disclosing more especially the seat-opening-covering slide with its actuating means. Fig. 7 is an enlarged detached fragmentary view showing more fully 40 the actuating means for said slide for covering the seat-opening.

In the carrying out of my invention I arrange conveniently to and preferably laterally of the ordinary dry closet or privy 1 a sifter chamber or inclosure 2, within which, 50 as indicated, is arranged in its upper portion a sifter or screen 3, preferably rectangular in general outline. Said sifter or screen is supported movably upon a roll or cylindric bar 55 3^a, secured or arranged in the casing or inclosure 2 at its rear side, and which sifter has

secured to an upward-extended rear portion thereof a rod or handle 3^b, extending forward out through said casing conveniently for grasping and actuation, as in operating the 60 sifter. Said sifter of course being of sufficiently less diameter in one direction than the interior cross-section of the casing 2 to permit it to have the requisite reciprocation, as in operating said sifter, may have its lateral portions extended, as at 3^c, or otherwise be adapted to be upheld while thus being actuated or operated, as will be readily appreciated. The bottom 3^d of the sifter 3 is hinged or pivoted, as at 3^{dd}, laterally to the 70 sifter-frame, to provide for the ready tilting of said bottom when said sifter is moved outward, as shown, as in Fig. 5, and to permit the dumping of the remaining coarse material after each sifting operation, as will be 75 readily understood. Said sifter-bottom has extending from its free end bar extensions 3^e, serving therefor the like purposes as the extensions 3^e do for the sifter, the latter underlying the former when the sifter, with its bottom, is in operative position.

Within the casing or inclosure 2, directly above the sifter or screen 3, is secured or fixed a board or platform 4, one edge of which, however, is removed distantly from the opposite wall or side of said inclosure or casing, thus leaving an opening at that point to provide for dividing up the ashes or other material which may be dumped into said casing from above, part falling upon said board and 90 part falling into said sifter. After the exhausting of the contents of the sifter by suitably operating the latter that portion of the ashes or other material which may have lodged upon the platform or board 4 may be 95 removed therefrom by a scraper 4^a, resting edgewise upon the board 4 and actuated by a suitable handle 4^b, extending through the casing 2, and said material caused to fall into the sifter for treatment, as the previous contents of said sifter. In the lower part or bottom of the casing or inclosure 2 is arranged or provided to receive the sifted ashes or other material a trough 5, flanked upon opposite sides by downward and inward sloping 100 boards or deflectors 5^a, with their lower edges resting upon the upper edges of said trough to direct or conduct whatever ashes may fall thereon into said trough. Arranged within said trough is a conveyer 6, having spiral 105 blades or wings 6^a to provide as said conveyer is actuated for the endwise feeding or

delivery of the contents of said trough out through an opening 6^b in the casing 2 into an elevator presently described. Said conveyer has its shaft suitably journaled in opposite 5 sides of the casing 2, with one end extending beyond said casing and through the lower end of the inclined trunk or housing 8^a of an elevator 8, comprising an endless belt of buckets or carriers 8^b. Said projecting or extending 10 end of said conveyer-shaft has secured thereto within said end of said elevator-trunk a sprocket wheel or pulley 8^c, encompassed by said belt or buckets 8^b, whereby it is obvious as the last-noted is operated, as 15 presently explained, said conveyer-shaft will be simultaneously actuated, and thus provide for the delivery of the contents of the trough 6 into the buckets of the elevator for the elevation thereof up through said trunk 20 for a purpose later described. Said elevator-trunk or housing 8^a has also arranged in its upper end a sprocket wheel or pulley 8^d, secured upon a shaft 8^e bearing therein, and which pulley or wheel is also encompassed by 25 the endless belt or buckets 8^b, and which shaft has its forward end adapted to be readily actuated by hand for operating said endless belt of buckets constituting the elevator. With their upper meeting ends communicat- 30 ing with the corresponding end of the tank 8^a are two divergent chutes or spouts 9, whose lower ends deliver into the excrement-box 10. The spouts or chutes 9 have arranged or hung therein at their point of convergence a plate- 35 valve 9^a, adapted to be suitably actuated by hand to direct the flow of the elevated ashes or other material from the elevator into either chute or spout 9, as may be desired, in delivering the same into the excrement chamber or 40 box as an absorbent and deodorizer.

The privy-seat 10^a has arranged upon its under side, so as to permit of the closing of the opening therein after use, a slide 11, having depending therefrom a stirrup or staple 11^a, 45 within which plays and which is engaged by the lateral portion of a bent or crank arm 12^a of a rock-shaft 12, suitably supported in the front side of the privy and having secured to its outer end an arcuate foot-lever 13. Said 50 lever, as indicated, may be conveniently operated by applying the foot thereto in effecting the movement of the slide 11, as in opening or closing the opening in the seat for obvious purposes. The crank-arm 12^a, being 55 arranged within the privy box or chamber, has its vertical portion so inclosed or guarded by incasing it in any suitable way as to isolate or remove it from contact with the ex- 60 crement as the latter accumulates in said box or chamber. Also for purposes of ventilation a pipe, preferably of sheet-iron and about three inches in cross-section, may be ar- 65 ranged at the rear of the closet or privy upon the outside with its lower end extending thereinto under the seat formed by the top

of the excrement-box and its upper end terminating a suitable distance above the closet-roof.

Latitude is allowed as to details herein, as they may be changed as circumstances suggest without departing from the spirit of my invention. 70

I claim—

1. In a device of the character described, an excrement-chamber, a sifter, with its casing, provided above said sifter, with a platform, with one edge removed distantly from the opposite wall of said casing, a conveyer arranged below said sifter and adapted to receive the sifted material from said sifter, and 80 an elevator adapted to actuate said conveyer and deliver into said excrement-chamber. 75

2. In a device of the character described, an excrement-chamber, a sifter having a pivoted bottom, with arm or bar extensions at 85 one end, adapted to be supported upon the sifter-inclosure, means arranged below said sifter and adapted to convey the sifted material from said sifter, means adapted to elevate the conveyed material and deliver it 90 into said excrement-chamber.

3. In a device of the character described, an excrement-chamber, a sifter and an inclosing casing therefor, said casing having secured therein just above said sifter, a platform or board with one edge removed distantly from the opposite wall of said casing, and a scraper arranged upon said board or platform and having a handle extending through said casing, means for conveying 100 away the sifted material and means for elevating said material and delivering it into said excrement-chamber. 95

4. In a device of the character described, a sifter and its inclosing casing, said sifter having bar or arm extensions at one end adapted to rest upon a cross-bar of said casing, and a handle for actuating said sifter, extending through said casing. 105

5. In a device of the character described, 110 an excrement-chamber, a sifter, an inclosing casing therefor, a conveyer arranged within said casing and below said sifter, an elevator effective to actuate said conveyer and deliver the material conducted away by said conveyer to a point above said excrement-chamber, and a bifurcated "trunk" with its branches delivering at different points into 115 said excrement-chamber, said "trunk" or chute being equipped with a plate-valve 120 adapted to direct the elevated material, from the upper end of said "trunk" into either of said branches.

In testimony whereof I have signed my name to this specification in the presence of 125 two subscribing witnesses.

JOHN R. KOONS.
